UNITED STATES PATENT OFFICE.

EVERETT E. SWINEY, OF CHICAGO, ILLINOIS, ASSIGNOR TO KNAPP BROTHERS MANUFACTURING COMPANY, OF CHICAGO, ILLINOIS, A CORPORATION OF ILLINOIS.

WALL CONSTRUCTION.

Application filed September 24, 1923. Serial No. 664,365.

To all whom it may concern:

Be it known that I, EVERETT E. SWINEY, a citizen of the United States, and a resident of the city of Chicago, in the county of Cook and State of Illinois, have invented 5 certain new and useful Improvements in a Wall Construction; and I do hereby declare that the following is a full, clear, and exact description of the same, reference being had 10 to the accompanying drawings, and to the numerals of reference marked thereon, which form a part of this specification.

This invention relates to a wall construction adjacent doorways, windows and the 15 like, for buildings.

In the past, it has been customary to enclose the margins of the walls, especially the plastering adjacent the door ways, in metal casings which contact the door frame; 20 and when the doors would be slammed shut, the jar transmitted to the metal casings would frequently crack or damage the plaster.

This invention is designed to overcome 25 this defect and at the same time provide a hollow chamber in the wall adjacent the door for receiving the electric wiring.

It is therefore an object to provide a 30 stress receiving member for protecting the plastering adjacent the doors and absorbing the shock or jars of the door, and simultaneously providing a wire conduit passage or chamber.

With these and other objects in view 35 which will become more apparent in the following description and disclosures, this invention comprises the novel structure and combinations hereinafter described and more particularly pointed out and defined in the appended claims.

40 In the accompanying drawings which illustrate a preferred embodiment of this invention and in which similar reference numerals refer to similar features in the different views:

45 Figure 1 is a fragmentary elevational view of a door with the novel wall construction adjacent thereto.

Figure 2 is a fragmentary horizontal section through a wall substantially upon the 50 line 2—2 of Figure 1 upon an enlarged scale.

55 Figure 3 is a perspective view of a metal casing for encasing the margin or plastering at the end of the wall.

In referring now to the drawings which illustrate one embodiment of this invention, the reference numeral 1 represents a wall finished with the usual plaster coatings 2. Where there is to be an opening in the wall 60 to provide space for a door or window, the end of the wall is usually provided with a wooden border or end member 3 constituting a part of the frame of the opening. This end member 3 which is usually termed the 65 "buck," is shown as partially covered at its sides by the plaster 2.

The ends or margins of the plaster 2 are usually incased in metal retainers, and in Figure 3 there is illustrated a novel form of 70 metal retainer comprising a stamped metal form having a base portion 4 provided with filler holes 5 and marginal spaced dovetail parts or members 6 provided with upwardly struck tongues 7 which are adapted to be 75 embedded in the plaster coating and conjointly with the dovetail members 6 serve to securely anchor the metal retainer in the plaster coating. The base 4 is provided with a flange 8 at right angles thereto; the 80 width of the flange 8 corresponding to the thickness of the plaster coating and being provided with a marginal lip 9 adapted to overlie the outer edge or border of the plaster coating in flush relation therewith. The 85 flange 8 is preferably provided with a series of filler holes 10 for the plaster. These metal retainers give shape and permanency to the ends of the plaster coatings. They 90 are applied as shown in Figure 2 with the base portion partially abutting the buck 3 and with the flanges 8 forming substantially the ends of the plaster coatings which are applied after the retainers have been properly positioned and anchored in the partition by means of nails 11 or the like.

95 It should be understood that the afore-described construction may form one or two sides of the door opening and the top thereof. In the drawings there is only illustrated the construction at the unhinged edge 100 of the door; Figure 1 however shows the construction also continuing over the top of the door.

A door frame is usually placed in the 105 opening thuswise provided and the door hinged to said frame. In Figure 2 the reference numeral 12 designates the frame member forming the unhinged side of the door opening, and 13 represents the door jamb 110

with the door 14 abutting thereagainst. The frame member 12 is usually spaced a short distance from the buck 3 by means of spacing members 15.

5. In the past it has been customary to extend the plaster coatings and metal retainers into contact with the frame member 12; consequently, the jars arising from shutting or slamming the door would be transmitted to 10 the metal retainers and plaster coatings and frequently cause the plaster coatings to crack. To overcome this objection and to also provide a space for the electric wire conduits, this invention contemplates spacing 15 the ends of the plaster coatings a sufficient distance from the door frame member 12, and extending a resilient metal plate or strip of suitable form from the plaster coatings to the door frame. In the illustrated form 20 of this invention, the plaster coatings partially overlap the bucks 3, and metal plates or strips 16 overlap the end margins of the plaster coatings with their overlapping margins slightly crimped inwardly, and they extend 25 toward the door frame; the extending ends being suitably bent into contact with the door frame member 12, thuswise providing a hollow space in which the wire conduits 17 may be placed. The metal strips 30 or plates 16 are preferably anchored to the bucks 3 by means of screws 18 having their heads countersunk in the said plates.

These plates 16 form jar or shock absorbing plates in that they absorb the jars and shocks of the door and transmit the same to a large extent to the bucks 3 through the screws 18; the ends of the plates 16 that overlap the plaster coatings not being combined with said plaster coatings so as to 35 transmit a cracking force thereto.

It is apparent that the plates 16 form hollow shock absorbing extensions to the plaster coatings that prevent the same from cracking and at the same time they provide suitable spaces for the wire conduits.

I am aware that numerous details of construction may be varied through a wide range without departing from the principles of this invention, and I therefore do not pur- 40 pose limiting the patent granted otherwise than necessitated by the prior art.

I claim as my invention:

1. The combination with the frame of a door opening in a plastered wall, of means 45 for protecting said wall from the shocks of the door, comprising a flexible shock absorbing member bridging the gap between said wall and frame.

2. The combination with a door frame and wall adjacent thereto, of a resilient shock 60 absorbing member for protecting the wall comprising a metal member overlapping the wall and loosely contacting with said frame.

3. In a plastered wall construction for doors or the like having an encased margin 65 for the plaster, a metal strip overlapping said encased margin, and extending therefrom into contact with the door frame.

4. The combination with a plastered wall having an end buck, and a frame defining an 70 opening adjacent thereto but abutting said end buck, of a shock absorbing member fixed to said buck and bridging the gap between said wall and frame and effective for transmitting vibrations to said buck.

5. The combination with the frame of a doorway and a plastered wall, of a metal extension member forming a continuation of said wall and having sliding contact with said frame, for the purpose described.

6. The combination with a plastered wall and a frame at the end of said wall, of a metal structure connecting said frame and wall and defining a space for wiring, said metal structure also acting as a shock absorbing member, for the purpose described.

7. The combination with a wall having an end buck and a frame adjacent thereto in spaced relation but abutting said end buck, of a plaster coating on the wall extended partially to overlie the buck, and a resilient trim of sheet metal secured to the buck with one edge lapped over the adjacent plaster edge, the opposite trim edge being turned toward the frame to rest thereupon thereby 95 to bridge the gap between the frame and the buck and to define a space for wiring.

8. The combination with a wall having an end buck and a frame adjacent thereto in spaced relation but abutting said end buck, 100 of a plaster coating on the wall extended partially to overlie the buck, means for protecting the plaster coating along its edge adjacent to the buck, and a trim extending from said protecting means to the frame, 105 having a connection with the buck, the trim being lapped past the protecting means to conceal the same and to define a space for wiring.

In testimony whereof I have hereunto 110 subscribed my name in the presence of two subscribing witnesses.

EVERETT E. SWINEY.
